PLAYGROUND CLIMBER

Claude W. Ahrens, Grinnell, Iowa

Filed Sept. 28, 1962, Ser. No. 71,896

Term of patent 14 years

(Cl. D34—5)

FIG. 1

FIG. 2

FIG. 3

FIGURE 1 is a front perspective view of a playground climber showing my new design;

FIGURE 2 is a side elevation view;

FIGURE 3 is a top view;

FIGURE 4 is a front elevation view; and

FIGURE 5 is a rear elevation view.

I claim:

The ornamental design for a playground climber, substantially as shown.
